UNITED STATES PATENT OFFICE.

WONG ALDON, OF LOUISVILLE, KENTUCKY.

FIGURE TOY.

Application filed April 14, 1923. Serial No. 632,145.

To all whom it may concern:

Be it known that I, WONG ALDON, a citizen of China, residing at Louisville, in the county of Jefferson and State of Kentucky, have invented new and useful Improvements in Figure Toys, of which the following is a specification.

This invention relates to improvements in toys and particularly to a toy simulating a drummer boy containing mechanism for operating the drum sticks.

An object of the invention is to provide a toy having supporting legs mounting the operating mechanism within the body of the toy carried by the supporting legs for firmly supporting said mechanism during its operation.

A further object of the invention resides in providing a novel connection between the motor of the operating mechanism and the arms of the toy for moving the arms to operate the drum sticks carried thereby to produce a drumming movement on the drum carried by the body.

Another object of the invention is to provide a special means for controlling and governing the operation of the motor and the arms.

The invention includes other objects and improvements in the details of construction which are pointed out in the following description and claim and shown in the accompanying drawing in which;

Figure 1 is an elevation of the toy simulating the drummer boy.

Figure 2 is a sectional view of the body portion of the toy showing the motor mechanism.

Figure 3 is a sectional view through the body portion taken at right angles to Fig. 2 showing the manner of securing the body to the support.

Figure 4 is a detail sectional view illustrating the limited rotative connection between the hands and the arms.

The drummer boy generally indicated at 1 has a pair of legs 2 carrying feet 3 adapted to form a support for the figure and the motor mechanism indicated at 4 mounted in the framework 5 carried by the legs and concealed in and supporting the jacket or body covering 6 of the figure. A pair of trousers 7 are secured to the jacket 6 and cover the legs 2 which are formed of a single wire bent intermediate of its ends to form the two substantially parallel leg por-

tions as clearly illustrated in Figures 1 and 2. A crank shaft 8 is rotatably mounted in the upper end of the jacket 6 and beyond the jacket is bent to form the arms of the figure 60 as indicated at 9. Sleeves 10 are secured to the jacket 6 over the arms as indicated in Figure 1. Fig. 4 illustrates that hands 11 are mounted on the ends of the arms for a limited rotative movement thereon to provide sufficient free movement of the drum sticks 12 with respect to the arms to strike the drum 13 in the oscillating movement of the arms. The member 8 is formed with a 70 crank 14 within the jacket 6 for a purpose to be described.

The motor mechanism 4 above mentioned includes a coil spring 15 having one end secured to the frame 5 and the other end secured to the shaft 16 carrying the gear 17 and rotatably mounted in the frame for transmitting the power from the spring to rotate the shaft 18 mounting pinion 19 meshing with gear 17 to the member 8 through the link 20 connected with crank 80 14 and the offset end 21 of shaft 18. The rotation of the shaft 18 is governed by an escapement mechanism 22 including a frame 23 secured to frame 5 in which is mounted a pin 24 carrying an oscillating member 25 85 provided with a weight 26 to retard the motion of the member. This oscillating member is provided with a pair of pawls 27 adapted for cooperation with an escapement wheel 28 to alternately engage the teeth of 90 said escapement wheel which is mounted on shaft 18 for governing the rotative movement of said shaft in a well known manner.

The jacket 6 is preferably formed in sections to enable assemblage of the parts and is provided at 29 with openings to receive lugs 30 which are bent over as indicated in Figure 3 to secure the jacket sections to the frame 5 in assembled relation. The head of the figure indicated at 31 is secured to the upper end of the body as indicated in Figure 1.

By tensioning the spring through the operation of the key 32 mounted in the frame 5 and projecting through the jacket as clearly shown in Figure 1 the motor mechanism may be set in operation to produce an oscillating movement of the arms up and down for operating the drum sticks to hit the drum and thereby simulate a drummer. The movement of the drum sticks and hands

relative to the arms compensates for any inaccuracies in the oscillating movement of the arms so that the sticks will strike the drum in every oscillation of the arms. The 5 weighted oscillating member prevents a too rapid oscillation of the arms which would interfere with the proper drumming movement. It is to be noted that the feet 3 are so formed that the weight of the entire figure will be carried and balanced thereby so that the figure may be placed upon a table or other convenient place during the operation of the motor mechanism to play the drum. It is to be further noted that the motor mechanism is directly mounted on the legs to provide a firm support therefor and reduce a tendency of the figure to vibrate in operation.

What is claimed as new is:

A drumming toy comprising a figure in the form of a drummer boy having a body, legs and sleeves, a spring motor mounted in the body, a crank shaft extending through the body and having arms extending through said sleeves and having connection with said motor, hands having a limited rotative connection with the ends of said arms, drum sticks carried by said hands, a drum carried by said body and engaged by said sticks, and a U-shaped supporting member carrying said motor and having feet, the limited rotative connection between said hands and said arms forming a means to insure striking of the drum by the sticks on each movement of the arms.

In testimony whereof I affix my signature.

WONG ALDON.
